[57] CLAIM

The ornamental design for binoculars, as shown and described.

DESCRIPTION

FIG. 1 is a perspective view of the binoculars showing our new design in a completely folded condition;

FIG. 2 is a perspective view of said binoculars in a first partially unfolded condition;

FIG. 3 is a perspective view of said binoculars in a sequentially second partially unfolded condition;

FIG. 4 is in perspective view of said binoculars in a completely unfolded condition;

FIG. 5 is a top plan view of said binoculars in said completely unfolded condition of FIG. 4;

FIG. 6 is a bottom plan view of said binoculars in said completely unfolded condition of FIG. 4;

FIG. 7 is a front elevational view of said binoculars in said completely unfolded condition of FIG. 4;

FIG. 8 is a rear elevational view of said binoculars in said completely unfolded condition of FIG. 4;

FIG. 9 is a right side elevational view of said binoculars in said completely unfolded condition of FIG. 4;

FIG. 10 is a front elevational view of said binoculars in said completely folded condition of FIG. 1;

FIG. 11 is a rear elevational view of said binoculars in said completely folded condition of FIG. 1;

FIG. 12 is a right side elevational view of said binoculars in said completely folded condition of FIG. 1;

FIG. 13 is a top plan view of said binoculars in said completely folded condition of FIG. 1; and,

FIG. 14 is a bottom plan view of said binoculars in said completely folded condition of FIG. 1.

The left side elevational view in the completely unfolded condition is a mirror image of said right side of FIG. 9, and the left side elevational view in the completely folded condition is a mirror image of said right side of FIG. 12.
